UNITED STATES PATENT OFFICE.

JAMES H. SMITH, OF CHICAGO, AND AUGUSTUS BROWN, OF ELGIN, ILLINOIS, ASSIGNORS TO JAS. H. SMITH & CO., OF CHICAGO, ILLINOIS, A CORPORATION OF ILLINOIS.

PLATE-HOLDER.

SPECIFICATION forming part of Letters Patent No. 756,422, dated April 5, 1904.

Application filed June 26, 1903. Serial No. 163,264. (No model.)

To all whom it may concern:

Be it known that we, JAMES H. SMITH, residing at Chicago, Cook county, and AUGUSTUS BROWN, residing at Elgin, in the county of 5 Kane, State of Illinois, citizens of the United States, have invented new and useful Improvements in Plate-Holders, of which the following is a specification.

Our invention relates to plate-holders used 10 in photographic cameras.

The use of our improvements obviates the necessity for removing and laying aside a loose door or back and afterward replacing and fastening the same when the plate is 15 changed or the releasing, opening, closing, and fastening of a hinged door or back when used with a stiff slide.

The invention includes, first, a rest for the 20 sensitized plate when placing it on the adjusting-bars; second, a movable rabbet to retain the plate on the upper bar; third, means to hold the plate in its proper focal plane; fourth, means to adjust and removably hold the bars at predetermined vertical points, and, fifth, 25 means to control and hold the plate laterally when centering the plate.

The accompanying drawings illustrate the 30 invention, Figure 1 being a front elevation of a plate-holder embodying our improvements and with the curtain-slide almost entirely raised. Fig. 2 is a fragmentary view of the central part of the same enlarged, but without the sensitized plate; and Fig. 3 is an 35 enlarged vertical section of the holder on line $\alpha\alpha$ of Fig. 1.

The various features of the invention are 40 referred to by letters, similar letters denoting corresponding parts in the different views.

The letter A indicates the frame of our 45 plate-holder. It has a permanent back α and is furnished with a curtain-slide B.

C is the upper and D the lower horizontal 50 plate-centering bars. These bars are fixed at their ends to vertical strips c and d , respectively, on which are projections c^8 and d^4 to move in the vertical slots c^1 and d^1 , respectively, in the frame A. These strips c and d may be separated sufficiently to permit the insertion 55

between them of a pinion and be provided with notched edges to engage this pinion, if 50 so desired. The lower bar D has a groove d^2 to receive the plate P and a vertical extension or plate-rest d^3 of the inner rabbet to facilitate the introduction of the plate. The upper bar C has an extended inner rabbet or 55 plate-rest c^2 and an adjustable outer rabbet c^3 , which we hold in place by a lug c^4 , fixed on the bar C, and render movable by the finger-slots c^5 . A recess c^6 in the end of the rabbet c^3 and a stop-pin c^7 in the bar C limit the 60 movement of the rabbet c^3 . The lower edge of the plate P may thus be placed in the groove d^2 and its upper edge rest upon the upper rabbet c^2 and be made secure by drawing down the adjustable rabbet c^3 . 65

That feature of our improvement by which we adjust and removably hold the bars at predetermined vertical points may be attained by various devices which may be attached to and move with either bar and be provided 70 with means to engage a fixed part, as the back of the plate-holder. Two leaf-springs are readily adapted for this purpose, but for convenience we prefer to use one leaf-spring E, whose lower end is fastened to the lower 75 bar D, and whose upper end curves forward and exerts a slight pressure upon the back of the plate P, by which the plate is held steadily in position. A lug or pin e projects from the back of the spring E and is adapted to 80 engage recesses or holes f in the back α or in a plate F, fixed on the back α . The scale-figures "4," "5," &c., and the index e' indicate the place at which the lower bar must be stopped to accommodate a plate of a given 85 size.

G is a wire spring-catch or other equivalent means made laterally movable on the lower bar D and having an end g bent to engage notches in the outer rabbet of the lower bar 90 or in a plate h , provided with a scale fixed on said bar. Our preferred form for this device is a strip g' , sliding horizontally in a groove g^2 in the front of the lower bar below the plate-rabbet. To this strip g' is attached the 95 spring G, already described. The bent por-

tion *g* of this spring extends across the groove *d*² in the lower bar and forms a stop or rest for the plate *P*.

Having now described our invention, what we claim, and desire to secure by Letters Patent, is—

1. In a plate-holder having horizontal plate-bars, an adjustable outer rabbet on either of said bars, said rabbet having recesses in its ends, a lug to hold said rabbet in place, and stop-pins in the bar to engage said recesses for the purpose stated.

2. In a plate-holder having vertically-movable plate-bars, the combination with either of said bars of means to stop the same at a given point and to exert a slight pressure against the plate on said bars as described.

3. In a plate-holder an upper and a lower movable plate-bar, a spring attached to either of said bars and having its outer end curved to slightly press against the plate in said bars, substantially as herein described.

4. In a plate-holder having a fixed back provided with recesses and an upper and lower plate-centering bar, a leaf-spring attached to the lower bar and a projection on the back of

said spring adapted to engage said recesses in the back of the plate-holder.

5. In a plate-holder having horizontal plate-bars provided with notches in the front rabbet of one of said bars, a horizontally-adjustable spring on said bar adapted to engage said notches and to prevent lateral movement of the sensitized plate as herein set forth.

6. In a plate having horizontal plate-bars, a plate on the lower bar having notches in its upper edge and a longitudinal groove in its front side, a strip movable in said groove, and a spring on said strip having a bent end adapted to engage said notches and prevent lateral movement of the sensitized plate.

In testimony whereof we have signed our names to this specification in the presence of two subscribing witnesses.
